CLAIM

I claim the ornamental design for a lower member of an advertising carrying body for use on a filler gun, as shown and described.

DESCRIPTION

FIG. 1 is a top, front perspective from one side of the lower member of the advertising carrying body;

FIG. 2 is a bottom, side perspective view from said one side of the lower member;

FIG. 3 is a rear perspective view of the lower member;

FIG. 4 is a bottom perspective view of the lower member; and,

FIG. 5 is a top, front perspective view from the other side of said lower member.
